ADJUSTABLE SKIRT FORM

Thomas H. Smith, Oklahoma City, Okla.

Application October 8, 1936, Serial No. 104,723

7 Claims. (Cl. 223—69)

This invention relates to adjustable skirt forms used in cleaning and reblocking skirts and particularly used in treating the skirts of two-piece knit suits.

5 The purpose of this invention is to provide a skirt form which has relatively few parts; which will hold the skirt in shape without stretching it, and which is particularly easy to adjust.

A further object is to provide a skirt form 10 which is adjustable to suit the length of the skirt and particularly which is adjustable to secure the correct conformity of the form to the individual shape or cut of the hips of the skirt being treated, and in which the various adjustments may be quickly made.

A still further object is to provide a structure of this character in which each side bar of the form is constituted of two sections hinged to each other, whereby the upper or hip sections may be shifted into a plurality of positions relative to the lower or skirt sections, and whereby the lower cross bar which engages the lower edge of the skirt may be adjusted longitudinally in conformity to the length of the skirt.

25 Other objects will appear in the course of the following description.

My invention is illustrated in the accompanying drawings wherein:—

Figure 1 is a face view of my improved skirt form showing the parts in one of these adjusted positions.

Figure 2 is a side elevation of the structure shown in Figure 1, the parts being broken away.

Figure 3 is an elevation partly broken away 35 of the form shown in Figure 1, but adjusted to secure a different position of the parts.

Figure 4 is a top plan view of the cross bar, the side pieces 22 and the tubular member and rod being in section.

40 Referring to these figures, 10 designates a medially disposed tubular element and 11 designates a cross bar having an aperture through which the tubular element passes. The cross bar has a longitudinally extending opening 12 at each 45 end and the side walls of each opening are slotted at 13. The tubular member 10 is adjustable through the cross bar and is held in adjusted position by the set screw 14 extending through the cross bar. The cross bar is provided with a plurality of skirt engaging hooks 15, there being two rows of these hooks and the hooks extending outward. Extending through the tubular member 10 is a longitudinally adjustable rod 16. The tubular member is provided with a handle 17 at its lower end and the rod is provided with a

handle 18. The tubular member adjacent its lower end is provided with a set screw 19 which engages the rod and holds the rod in adjusted positions. Forming part of the tubular member 10 and projecting laterally and upwardly therefrom are the ears 20 and pivoted to these ears are the links 21 which normally extend upward and outward.

Extending through the openings 12 are the lower ends of two form sections, each designated 10 22. Pivoted to the upper ends of these lower form sections are the upper form sections 23, the latter form sections being slightly bowed and at their lower ends alining with the lower form sections 22. Pivoted to the upper ends of the 15 upper form sections 23 are the links 24 and these in turn are pivotally connected to metallic lugs 25 extending out from the upper end of the rod 16. The lower ends of the upper form sections 23 carry the downwardly and inwardly 20 extending lugs 26 and the links 24 are pivoted at their upper ends to these lugs. The lower ends of the lower form sections 22 are longitudinally slotted at 27 and passing through these longitudinal slots 27 and through the slots 13 25 are the bolts or binding screws 28.

It will be seen that with this construction, the cross bar 11 may be shifted vertically with relation to the lower sections 22 and that these lower sections may be shifted outward at their lower ends relative to the cross bar and held in these shifted or adjusted positions by the bolts 28. The bolts 28 or equivalent devices also constitute pivots upon which the lower section 22 may rock when the upper ends of the lower sections are forced outward or drawn inward by 30 the links 21.

Preferably the links 21 and 24 are made of ash wood. As illustrated, the links 24 are cleft at their lower ends to embrace the lugs 25, 40 while the upper ends of the links are cleft to embrace lugs 29. These in turn are inserted in slots or clefts 30 formed in the upper ends of the sections 23. These lugs 29 may be made of any suitable material as, for instance, oak veneering. Preferably, the lugs 26 will also be made of oak veneering. These lugs 26 each at its outer end is inserted in a cleft 30, as shown in Figure 2, formed in the lower end of the corresponding upper section 23. The body portion 45 of each lug which is inserted in said cleft extends downward into a cleft formed in the corresponding lower section 22 and is pivoted thereto by means of the pin 31. Thus each upper section 23 can be turned at an angular relation 50 55

to the lower section by shifting upward on the tubular member 10, which forces the lower ends of the upper section outward or draws them inward relative to the lower sections. The upper 5 ends of the upper sections may be forced outward or drawn inward by shifting the rod 16 relative to the tubular member 10.

The lugs 20 and 25 will preferably be made of brass as will be the tubular member 10 and the 10 rod 16. Preferably, the pipe 10 and the rod 16 will be covered with knitted tubing or otherwise coated so as to prevent staining the goods placed on this form, which staining would occur from the condensation of the steam on the metal.

15 The main object of this skirt form is to reshape and reblock knitted skirts to original size after cleaning. When the skirt has been only dry-cleaned, which does not shrink or stretch the garment, the form is set to the exact size of the skirt. 20 The skirt is then placed on it and then the skirt on the form is steamed and dried. If, however, it is necessary to wet-clean the skirt, the skirt is first measured and the form set to the size and shape desired, the skirt is wet-cleaned on the 25 form and dried, which thus prevents shrinkage. The form can be adjusted to all sizes of skirts by adjusting the hips larger or smaller, adjusting the size of the upper end of the form which fits the waist and adjusting the length of the form to the 30 skirt being treated.

It is particularly important that links 21 be connected to the lower end of sections 23 instead of to the upper ends of the sections 22 for the 35 following reason: Waist and hips are set to measure and if links 21 were connected to the upper sections 22, adjusting the form wider at the hem would cause the form to be narrower at the hips and vice versa. For this reason, the links 21 are connected to the lower end of the members 23.

40 It is obvious that by reason of the particular construction described, the form may be readily adjusted to suit any length of skirt and any width of skirt and that by adjusting the tubular rod 10 and the rod 16 relative to each other, the device 45 may be adjusted in conformity to any desired shape of skirt so that while holding the skirt expanded, there will be no stretching action on the skirt. It is understood, of course, that the lower edge of the skirt is engaged by the hooks 15 while 50 the upper portion of the skirt is engaged by the upper sections 23.

It will be understood that while I have illustrated certain details of construction and arrangement of parts and particularly described 55 certain materials as being used, yet these details might be modified in many ways without departing from the spirit of the invention as defined in the appended claims.

60 What is claimed is:—

1. A skirt form, including a cross bar having means for engaging the lower edge of a skirt, lower rigid form sections adjustable upon the cross bar either longitudinally thereof or vertically with relation thereto, upper rigid form sections 65 separate from but pivoted to the upper ends of the lower sections, the upper form sections being slightly bowed upward and inward, manually operable means for adjusting the lower ends of the upper sections inward or outward, manually operable means for adjusting the upper ends of the upper sections inward or outward, and means for holding said sections in adjusted positions. 70

2. A skirt form, including a cross bar having 75 means for engaging the lower edge of a skirt, the

ends of the cross bar having elongated openings, the side walls of said openings being longitudinally slotted, lower form sections extending at their lower ends through said openings in the cross bar and provided with longitudinally extending slots intersecting the slots of the cross bar, fastening means passing through the slots of the cross bar and the slots in said sections to thereby hold the lower sections in adjusted position upon the cross bar, said fastening means acting as pivots for the lower sections on the cross bar, upper hip form sections separate from but pivoted to the upper ends of the lower section in alinement therewith, the upper sections being slightly bowed upward and inward, manually operable means for adjusting the lower ends of the upper sections inward or outward, and manually operable means for adjusting the upper ends of the upper section inward or outward. 10 15

3. A skirt form, including a cross bar having 20 means for engaging the lower edge of a skirt, the ends of the cross bar having elongated openings, the side walls of said openings being longitudinally slotted, lower bodily rigid form sections extending at their lower ends through said openings in the cross bar and provided with longitudinally extending slots intersecting the slots of the cross bar, fastening means passing through the slots of the cross bar and the slots in said sections to thereby hold the lower sections in 25 adjusted position upon the cross bar, said fastening means acting as pivots for the lower sections on the cross bar, upper bodily rigid, hip sections separate from but having their lower ends pivotally engaged with the upper ends of the 30 lower sections, the lower ends of the upper sections being in alinement with the upper ends of the lower sections, manually operable means for adjusting the meeting ends of the upper and lower sections outward or inward, and manually operable means for adjusting the upper ends of the 35 upper sections outward or inward. 40

4. A skirt form, including a cross bar having hooks along its upper edge for engaging the lower edge of a skirt, the outer ends of the cross bar 45 having openings, lower bodily rigid form sections extending through said openings and adjustable toward or from the middle of the cross bar or vertically with relation thereto, bodily rigid upper hip form sections separate from but pivoted to 50 the upper ends of the lower sections in alinement therewith, the upper sections being bowed upward and inward, a tubular member adjustable longitudinally through the middle of the cross bar, links pivotally connected to the tubular member and pivotally connected to the lower 55 ends of the upper form sections, a rod extending through the tubular member, links pivotally connecting the upper end of the rod to the upper ends of the upper form sections, means for holding the rod in adjusted position relative to the tubular member, and means for holding the tubular member in adjusted positions relative to the cross bar. 60

5. A skirt form, including a cross bar having 65 hooks for engaging the lower edge of a skirt, said cross bar at its outer ends having longitudinally extending openings, the side walls of which are slotted, lower bodily rigid form sections disposed through said openings, each form 70 section being longitudinally slotted, bolts passing through the slots of the cross bar and through the slots of the lower form sections whereby the lower form sections may be adjusted upon the cross bar and held in adjusted position, said bolts 75

- constituting pivots, bodily rigid upper form sections separate from but having their lower ends pivotally engaged with the upper ends of the lower form sections, the upper sections being slightly 5 bowed outward and inward, a tubular member extending through the cross bar and adjustable therein, a set screw holding the tubular member in adjusted positions relative to the cross bar, the tubular member having ears, links pivoted 10 to said ears and to the lower ends of the upper form sections, a rod extending through said tubular member and having lugs at its upper end, links pivotally connecting said lugs to the upper ends of the upper form sections and a set screw 15 holding the rod in adjusted position relative to the tubular member.
6. A skirt form, including a wooden cross bar having means for engaging the lower edge of a skirt, the ends of the cross bar having openings, 20 the side walls of the openings being longitudinally slotted, lower wooden form sections extending through the openings of the cross bar and being longitudinally slotted, fastening members passing through the slots of the lower form sections 25 and the cross bar whereby the lower form sections may be held in adjusted positions upon the cross bar, said fastening means acting as pivots, upper slightly bowed sections disposed with their lower ends in alignment with the upper 30 ends of the lower form sections, the adjacent ends of the form sections being cleft, wooden inserts disposed within said clefts and pivotal connections between said inserts and the lower form sections, said inserts being formed to provide inwardly projecting lugs, the upper ends of the upper form sections being cleft, wooden inserts disposed within said clefts and constituting 5 inwardly projecting lugs, a tubular member passing through the cross bar and adjustable therein, the tubular member having laterally projecting lugs, wooden links pivotally connecting the last named lugs with the lugs on the lower ends 10 of the upper form sections, a rod disposed through the tubular member and having lugs at its upper end, links pivotally connecting said lugs with the lugs at the upper ends of the upper form sections, means for holding the rod in any ad- 15 justed position with relation to the tubular member, and means for holding the tubular member in adjusted position with relation to the cross bar.
7. A skirt form, including a cross bar having 20 means for engaging the lower edge of a skirt, rigid lower form sections adjustable upon the cross bar either longitudinally thereof or vertically with relation thereto, upper rigid hip form sections separate from but pivoted to the upper 25 ends of the lower sections, manually operable means for adjusting the upper ends of the upper sections inward or outward, and separate manually operable means for adjusting the upper ends of the lower sections and the lower ends of the 30 upper sections inward or outward.

THOMAS H. SMITH.
